PENCIL POINT SHARPENER

Antonio Cornish-Besa, Santiago, Chile

Application June 16, 1945, Serial No. 599,881

3 Claims. (Cl. 120—91)

1

This invention relates to pencil point sharpeners for mechanical pencils.

The principal object of the invention is to provide a sharpening device for use in connection with mechanical pencils, the device being adapted to sharpen the "lead" of the pencil without damaging the holder.

Another object is the provision of a sharpener of the character described which is of the simplest construction and which may be used with great ease, speed and precision.

A further object is the provision of a sharpener of the character described which may be mounted on a standard mechanical pencil without the necessity of making special provision for the mounting of the same.

Preferred embodiments of this invention are shown in the accompanying drawing in which—

Fig. 1 is a fragmentary view, partly in section, of the top of a standard mechanical pencil in which one of the preferred forms of the sharpening device is mounted;

Fig. 2 is a fragmentary view of the same pencil showing the sharpening device detached therefrom and being used to sharpen the "lead" of the pencil;

Fig. 3 is an enlarged sectional view of said sharpening device showing the mounting therefor;

Fig. 4 is a top view of said sharpening device showing the rotatable apertured disc through which the "lead" of the pencil is inserted during the sharpening operation; and

Fig. 5 is a view similar to that of Fig. 3 showing a second preferred form of sharpening device and the mounting therefor.

Referring now to Figs. 1 to 4 inclusive, the first form of sharpening device 10 is shown mounted in a standard mechanical pencil 11. The sharpening device proper comprises an abrasive member 12 and an apertured disc 13 rotatably mounted thereon. The member 12 is a unitary member made of abrasive material such as Carborundum. It is a solid of cylindrical shape whose diameter corresponds to the diameter of the standard eraser and eraser mounting 14 which is ordinarily carried by mechanical pencils of standard construction. The abrasive member 12 has an annular groove 15 formed in its top surface, said groove being cone shaped in cross section. Since the member 12 is made of abrasive material, the walls of said groove have abrasive properties. The disc 13 is rotatably mounted on the member 12 by means, for example, of a set screw 16. Reference to Fig. 4 will show that the disc is pro-

2

vided with a plurality of apertures 17 which may be of different diameters to accommodate "leads" of corresponding diameters. It will be noted that these apertures 17 are co-axial with the groove 15, reference being had here to the circular axis of the groove which extends through the apex of the cone.

The sharpening device thus described is mounted within a sleeve 20 which is the same sleeve in which the eraser and the eraser mounting 14 are mounted, the sharpening device being mounted at one end thereof and the eraser at the other end. This complete assembly, comprising the sharpening device, the eraser and the sleeve in which they are mounted, may be introduced into the barrel of the pencil 11 in the manner shown in Fig. 1. To use the sharpening device, this assembly is removed from the barrel of the pencil and the pencil point or "lead" 18 is inserted through an appropriate aperture 17 in the disc 13 as shown in Fig. 2, the assembly being normally held in the left hand and the pencil in the right. The pencil is then made to engage in movement of revolution as distinguished from movement of rotation as indicated by the arrow in Fig. 2. In consequence of such movement, the "lead" 18 is caused to travel in a circular path through groove 15, in abrading contact with the walls thereof. Only a few such revolutions are needed to sharpen the point to precision fineness. It should be noted here that the shape of the groove is predetermined to provide opposing abrasive surfaces of appropriate angular relationship. The sharpening device thus described is adapted to sharpen "leads" of different thickness to the same fine degree of sharpness at all times.

A second form of sharpening device 25 is shown in Fig. 5. The disc 26 of said sharpening device is identical with the disc 13 of the sharpening device first above described and it is mounted in precisely the same manner by means of a set screw 27. Unlike the abrasive member 12 above described, the abrasive member of the present device comprises two elements: an outer element 28 and an inner element 29 fastened. The element 28 has a circular outer wall. A hole having the shape of an inverted truncated cone is formed in said element 28 co-axial with its outer walls. The member 29 is shaped like a pair of truncated cones set base to base. Such being the case, when the member 29 is inserted into the hole formed in the member 28, a groove 30 similar in shape to the above described groove 15 is formed between said elements. The walls of said groove 30 are roughened or rendered file-like or

are surfaced with an abrasive coat. It is immaterial what the elements 28 and 29 are made of when the walls of their groove 30 are coated with an abrasive. The abrasive, however, need not constitute a coat. Instead the walls themselves may possess abrasive properties. In the preferred form of this invention the walls are made of hardened steel with a file type of surface. The sharpening device 25 is mounted on the closed end of a tumbler-shaped holder 31 by means of a screw 32. It will be seen that the screw engages only the element 29 and not the element 28. It is clear from Fig. 5, however, that when the element 29 is fastened to the holder 31, the element 28 is necessarily held in position with respect both to the element 29 and to the holder 31. When the sharpening device is assembled in this manner, it is not necessary that the element 28 be fused to the element 29 since they are held together by screw 32 in cooperation with the holder 31. The holder 31 performs the additional function of holding the eraser and eraser mounting 14 in precisely the same manner as the sleeve 20 holds this member in the assembly first above described. The sharpening device shown in Fig. 5 is used in the same way as the sharpening device shown in Figs. 1 to 4, inclusive.

Although both forms of sharpening devices above described include a rotatable disc, that disc may be dispensed with. It serves only as a handy guide for the pencil "lead" and also prevents the fine particles of "lead" which would normally adhere to the abrasive surfaces of the groove from soiling the hands or the pocket in which the pencil would normally be kept. It is clear that the device thus described is susceptible of many modifications without departing from the basic principles of the invention. For example, the elements 28 and 29 shown in Fig. 5 are two separate elements held together to form an abrasive surfaced groove 30.

I claim:

1. A pencil point sharpener for mechanical pencils, said sharpener comprising a sleeve reversibly mounted in the barrel of a mechanical pencil, a sharpening member affixed at an end of said sleeve, said sharpening member having an annular groove formed therein which is cone-shaped in cross-section and which has abrasive

walls, said sharpening member having an apertured disc rotatably mounted thereon coaxially therewith, the apertures in said disc being of a diameter substantially corresponding to the diameter of the pencil point of said mechanical pencil, and being arranged on a circular line which registers with the circular axis of the groove.

2. A pencil point sharpener for mechanical pencils comprising a member having an annular groove formed therein which is cone-shaped in cross section and which has abrasive surfaced walls, said member having an apertured disc rotatably mounted thereon, the apertures therein being co-axial with the circular axis of the groove, said member being mounted at the closed end of a tumbler-shaped member, said tumbler shaped member being adapted for mounting in the barrel of a standard mechanical pencil.

3. A pencil point sharpener for mechanical pencils, said sharpener comprising a sleeve reversibly mounted in the barrel of a mechanical pencil, a sharpening member affixed at an end of said sleeve, said sharpening member having an annular groove formed therein which is cone-shaped in cross-section and which has abrasive walls, said sharpening member having an apertured disc rotatably mounted thereon coaxially therewith, the apertures in said disc being of different diameters which respectively correspond to the diameters of pencil points of different thicknesses, said apertures being arranged on a circular line which registers with the circular axis of the groove.

ANTONIO CORNISH-BESA.
